UNITED STATES PATENT OFFICE

EUGEN ALBERT, OF MUNICH, GERMANY.

ETCHING PROCESS.

1,081,290.

Specification of Letters Patent.

Patented Dec. 16, 1913.

Application filed May 25, 1912. Serial No. 699,690.

To all whom it may concern:

Be it known that I, EUGEN ALBERT, a subject of the Emperor of Germany, residing at Kaufingerstrasse 11, Munich, Germany, have invented certain new and useful Improvements in Etching Processes, of which the following is a specification.

This invention relates to the process of etching metal plates for printing purposes and the like by means of acid in a bath, and has for its object to render the process more effective and more expeditious.

The etching process in most etching machines is achieved by violently agitating the acid on the surface of the object being etched in order to renew the particular molecules in action as frequently as possible in a given unit of time; the mechanical force of the movement also removes the oxid from the etched surface which would otherwise prevent the etching action.

Most of the constructions hitherto employed in carrying out the etching process, suffer from the disadvantage that steel and iron, or similar materials, can not be employed, even where considerable mechanical strains occur, owing to the action of the acid.

New conditions obtain in the application of the present process, a current of air being conducted against the plate or other object situated in the acid and a resistance being interposed either directly or indirectly in the path of the air current. When a direct resistance is interposed a violent whirling or ebullient movement of the acid occurs, but, if, say, a single air current is projected from a slit nozzle on to the liquid, an air furrow is produced and the resistance is an indirect one due to the deformation of the level surface of the liquid and the liquid trying to regain its original form. In this latter case the effect is attained that the particles of liquid move quickly over the surface of the plate under considerable pressure. The dimensions of the furrow, or air groove, produced depend on the velocity with which the compressed air issues from the outlet opening. The etching action varies considerably within the active zone of this air furrow. If we suppose that this air furrow is about two inches deep then it will be clear that the etching action on any object situated much deeper than two inches will not be very effective. On the other hand if the article to be etched be raised too

high, the air current will drive all the acid away from some areas of the object leaving the surface quit dry. Between these positions, there is what may be termed the active zone into which the article to be etched is brought, so that the violently agitated acid shall be able to remove the oxid formed. It is evident that in order uniformly to etch large areas, the article to be etched and the air outlet should be moved relatively to each other. If a direct resistance be opposed to the movement of the acid induced by the current of air applied as stated, the etching acid is broken up and the kinetic energy imparted to the particles of liquid is expended in the production of whirling movements. The agitating movement of the acid acquired in this whirling zone—that is the space between the air outlets and the resistance—can be restricted, while the acid situated outside of this zone is at rest on the upper surface. The intensity of the liquid agitation in the whirling zone depends on several factors. The air outlet may be varied; it may consist of a rose, or sprinkler, provided with a number of holes, but to avoid frictional losses, it may advantageously consist of slotted openings. Furthermore the intensity of the liquid movement on the surface of the object to be etched depends as before on the relative position of the parts; if, for example, the object is situated some six or seven inches below the surface of the acid, then the whole weight of liquid situated above the object would be opposed to the production of the whirling movement, and would diminish its effect; also considerable power is wasted if the distance between the air outlet and the object to be etched is too great; in both cases, a corresponding increase in the pressure of the compressed air is required in order to overcome the resistance. It will be seen therefore that either with or without a direct resistance opposed to the air current, it is advisable to arrange the object to be etched near the surface of the acid.

The accompanying drawing shows a practical means of applying my process in which a direct resistance is opposed to the air current, the said resistance being formed firstly, by a second air current, both air currents being of lineal form and converging toward the object to be etched, and secondly, by the object itself.

Figure 1 shows an arrangement in which the resistance is formed by an air current; and Fig. 2 is a modification in which the resistance is formed by the object to be etched, in this instance, a roller.

Referring to Fig. 1, *a* is a trough or tray which is filled up to *e* with acid; *c* is the flexible tube for supplying compressed air, *b* is the nozzle which conducts the air in 10 two converging currents against the object *d* to be etched, situated beneath the surface of the acid. *f* is the whirling or agitated zone and *g* the exhaust tube through which the injurious acid vapors can exhaust into 15 the open without the use of any fan, or the like, but merely owing to the pressure of the air blast within the saddle-shaped double nozzle *b*. Now in order that the etching process may be carried out uniformly, 20 the air current and the object to be etched must move relatively to each other, which is most easily obtained by slowly and uniformly moving the trough. In this arrangement the whole movement of the acid 25 takes place in the body of the blast nozzle and consequently the trough can be quite open and does not need any protecting device for preventing the splashing out of any acid. It is thus easily interchangeable for various 30 acids and the acid vapors can be exhausted without any expense through an exhaust tube by the current of air. According to this invention therefore, new constructive conditions are brought into play; only the 35 trough and the air outlet devices need be acid-proof, and none of the parts are exposed to any mechanical strain. Besides this example, many other arrangements are possible; any number of air outlets of any 40 desired shape may be provided and thus such a uniform distribution of the power of the air current, and whirling factor, be obtained that only a small equalizing movement of the article to be etched, or of the 45 blast, will be necessary, indeed in some cases no movement of either will be required.

In certain cases the object to be etched may constitute the resistance, as when etching a round body, for example a roller, or 50 the like. This modification is shown in cross section in Fig. 2, in which the roller *d'* dips below the surface of the acid *e'* in the trough *a'*, and air brought by the tube *c'* is blown from the side through the blast 55 nozzle *b*, *c* as far as possible along the whole breadth of the roller to be etched, so that the acid thus brought into movement strikes against the roller *d'* which forms a resistance. With intermittent action of the air 60 current an increased resistance may be formed by the liquid itself.

What I claim as my invention and desire to secure by Letters Patent is:—

1. The process of etching consisting in directing a current of compressed air on to the etching acid, producing a resistance to the said air current by the deformation of the liquid surface into a furrow, or air groove, placing a part of the object to be etched just beyond the surface of the acid in said furrow, and displacing the etched portion of said object and the air current in relation to each other, substantially as and for the purpose set forth. 65

2. The process of etching consisting in directing a current of air against the object to be etched placed just beneath the surface of the etching acid, and in opposing a resistance to the movement of the liquid displaced by the air current so that 70 the liquid is broken up and agitated, substantially as described herein. 75

3. The process of etching consisting in directing a current of air against the object to be etched placed just beneath the surface 85 of the etching acid, and in opposing a direct resistance to the movement of the liquid displaced by the air current by means of a second air current, substantially as and for the purpose set forth. 90

4. The process of etching consisting in directing a current of air against the object to be etched placed just beneath the surface of the etching acid, and in opposing a direct resistance to the movement of the 95 liquid displaced by the air current by means of a second air current the two said air currents converging toward the surface of the object to be etched, substantially as described herein. 100

5. The process of etching consisting in directing a current of air against the object to be etched placed just beneath the surface of the etching acid, and in opposing a direct resistance to the movement of the 105 liquid displaced by the air current by means of a second air current the two said air currents converging toward the surface of the object to be etched and being of a concentrated lineal character applied transversely of the object, and in producing relative to each other a movement between said object and the air blast, which movement has a longitudinal direction as regards the plate. 110

In testimony whereof I have affixed my signature in presence of two witnesses.

EUGEN ALBERT.
